UNITED STATES PATENT OFFICE.

EUGENE E. MITCHELL, OF WASHINGTON, DISTRICT OF COLUMBIA, ASSIGNOR
TO MATTIE INGRAHAM, OF WABASHA COUNTY, MINNESOTA.

TOY BOAT.

SPECIFICATION forming part of Letters Patent No. 707,148, dated August 19, 1902.

Application filed February 24, 1899. Serial No. 706,712. (No model.)

To all whom it may concern:

Be it known that I, EUGENE E. MITCHELL, a citizen of the United States, residing at Washington, in the District of Columbia, have 5 invented certain new and useful Improvements in Toy Boats; and I do hereby declare the following to be a full, clear, and exact description of the invention, such as will enable others skilled in the art to which it appertains 10 to make and use the same.

My invention relates to toys in general, and more particularly to movable toys, and has for its object to provide a novel and attractive toy which may be automatically dismembered when desired in imitation of an explosion, a further object being to provide means for producing a sound or sharp report at the time of the dismemberment.

In the drawings forming a portion of this 20 specification, and in which like letters of reference indicate similar parts in the several views, Figure 1 is a side elevation of a miniature boat constructed in accordance with my invention. Fig. 2 is a section on line 22 of Fig. 1.

Referring now to the drawings, in operating in accordance with my invention, I form a boat comprising a base-piece *a*, upon which are fixed bearings *b* for front and rear axles *c* 30 and *d*, having wheels thereon, the wheels of the front axle being arranged to rotate in conjunction with their axle.

Upon the base *a* are built up a number of sections *e* to form a boat, certain sections, as 35 shown in Fig. 2, being recessed to receive a cross-piece *f*, the position of which latter is substantially centrally of the boat and beneath the pilot-house, smoke-stacks, &c., so that if the cross-piece be raised violently a 40 general throwing apart of the structure will result. To accomplish this throwing apart of the structure in imitation of the result of an explosion, I place upon the axle *c* a drum *f'*, adapted to rotate with the axle. Attached 45 at one end to the drum and adapted to be wound thereon as the drum rotates is a cord *g*, attached at its other end to a pin *h*, held in guides *i* and *k* on the under side of the base *a*. The pin acts as a trigger, in connection 50 with a plunger *l*, passed vertically through a perforation in the base *a* and entering a space

m within the body of the boat. The plunger *l* is provided at its upper end with an enlarged head *n*, and intermediate said head and the base *a* and encircling the plunger is a helical spring *o*, the tendency of which when compressed is to raise the plunger. Through the lower end of the plunger is formed a perforation *p*, adapted to receive the pin *h*, which latter holds the plunger in a lowered position 60 with the spring *o* compressed. The plunger *l* is located directly beneath the cross-piece *f*, so as to strike it when released, and by raising it violently throws the boat in pieces. The head of the plunger is provided with a 65 recess, as indicated in dotted lines, to receive a cap such as is employed with toy pistols. A projection *r* upon the under side of the cross-piece *f* engages the cap when the plunger rises and explodes the cap, making the result more pleasing and realistic. Thus it will be seen that the plunger having been depressed to compress the spring and the pin being in position in the end of the plunger 70 the pieces of the boat may be put together to 75 form the complete structure. The cord being unwound from the drum *f'*, the boat is then moved along the floor in any desired manner, such as through the medium of a pulling-cord secured to a ring *s* at the bow, as shown. As 80 the wheels revolve the drum will have a like movement and will gradually wind up the slack cord. When the slack is taken up, a pull will be exerted upon the pin *h*, and as the boat is further moved the pin will be gradually withdrawn until when finally entirely 85 removed the spring *o* will be released, and the plunger rising violently against the cross-piece thereabove the cap will be exploded and the boat thrown violently apart, as in an 90 explosion.

It will be readily understood that instead of a boat any other structure may be built of sections and have similar mechanism for accomplishing a similar result and that, in connection with these different structures, I may employ such specific mechanism as may be deemed proper to accomplish the desired result. It will also be seen that the cord presents an adjustable releasing means, for the 95 reason that the farther the cord is drawn back the farther the boat may be drawn before

the spring will be released to throw the boat apart.

Having thus described my invention, what I claim is—

- 5 1. The combination with a separable structure comprising a base having the structure built thereon, said structure comprising a support having parts of the structure resting thereon, a plunger passed through the base and having a head adapted to receive an explosive cap, a projection on said support adapted to coöperate with the plunger-head to explode a cap carried by the latter, a spring arranged to throw the plunger upwardly, a
- 10 15 perforation in the plunger, a pin passed through the perforation to hold the plunger retracted, wheels for the structure and connections between said wheels and pin to with-

draw the latter and release the plunger, whereby it may rise and explode the cap and throw the parts of the structure apart.

2. A toy of the class described which represents a battle-ship provided with a central detachable deck portion on which the turrets, masts, davits and other deck - fixtures are loosely placed, and means upon and beneath said detachable deck portion for causing the representation of an explosion and the lifting of said detachable deck portion, substantially as shown and described.

In testimony whereof I affix my signature in presence of two witnesses.

EUGENE E. MITCHELL.
